UNITED STATES PATENT OFFICE.

JOSEPH S. H. LOVETT, OF TRENTON, NEW JERSEY, ASSIGNOR OF ONE-THIRD TO THEODORE PESSINGER PAYNE, OF NEWARK, NEW JERSEY, AND ONE-THIRD TO WILLIAM WALLACE NEAR, OF TORONTO, CANADA.

HOSE-MAKING MACHINE.

No. 889,939.

Specification of Letters Patent.

Patented June 9, 1908.

Application filed November 20, 1907. Serial No. 403,104.

To all whom it may concern:

Be it known that I, JOSEPH SCHENCK HOOKER LOVETT, of the city of Trenton, in the county of Mercer, in the State of New Jersey, one of the United States of America, have invented certain new and useful Improvements in Hose-Making Machines, of which the following is the specification.

My invention relates to improvements in hose making machines, and the object of the invention is firstly to deliver the canvas as fed by the automatic feeding machine into the proper position between the forming and winding rollers, as covered by my Letters Patent of the United States of America, numbered 682,588, and dated September 1, 1901, secondly, to automatically deliver the hose when made to the place of deposit and it consists essentially firstly, of a vertically movable table located between the frames of each section of the forming and winding rollers, a V-block movable longitudinally in a guide in the table and designed to receive the pole on which the hose is held, and to convey it from the grooved rollers forming part of the carrying table to between the forming and the winding rollers, and secondly of a plate located intermediately of the length of the table and also capable of longitudinal movement in guides therein, supplementary forming rollers mounted on the plate and designed to carry the pole and hose when wound from between the forming and winding rollers into grooved rollers designed to convey the completed hose from the machine, as hereinafter more particularly described by the following specification.

Figure 1 is a perspective view of two end portions of the winding and forming machine sections showing my device in cross section located intermediately thereof. Fig. 2 is a similar view of one end of the end section showing my device complete. Fig. 3 is a cross section of my machine. Fig. 4 is a detail showing means for automatically throwing the winding chuck into gear.

In the drawing like letters of reference indicate corresponding parts in each figure.

A is the winding and forming machine provided with the usual forming rollers A' and the winding rollers A². The winding and forming machines are built in sections, and between each section is located my device for transferring the hose from the grooved

wheel of the conveyer to between the winding and forming rollers, and from between the winding and forming rollers to the grooved wheels designed to convey the hose out of the machine.

Referring to Fig. 3 of the drawings, B is one of the grooved wheels of a conveying device (shown in dotted lines), by which the canvas is conveyed from the cutting machine to the winding and forming machine and which is described in a concurrent application. B' is a pole on which the hose is held and which is also shown by dotted lines.

I will now describe my means of conveying the hose from the wheels B to between the forming rollers and winding rollers A' and A² respectively, and then from the forming and winding rollers to the delivery wheels.

C is a table.

D is an air cylinder having a port D' extending down to the bottom of the interior and forming both an admission and exhaust port. The port D' is supplied with compressed air through the pipe D², the supply of air being controlled by the three way valve D³ (see Fig. 3).

D⁴ and D⁵ are the piston and piston rod respectively of the cylinder D.

E is an air cylinder supported horizontally on the top of the piston rod D⁵.

E' and E² are the piston and piston rod respectively of the cylinder E.

F is a grooved pulley secured to an arbor F' journaled in suitable bearings F² beneath the table C. The upper portion of the pulley extends through a slot C' formed in the table.

G is a block having a broad V-shaped notch at the top and a dovetail tongue at the bottom.

C² is a dovetail way extending longitudinally of the table. The tongue of the block C² is held in the way and is moved longitudinal therein.

H is an idler pulley journaled in the bracket H' secured beneath the table C.

H² is a cord secured at one end in the groove of the pulley F and at the other end to the block G.

H³ is a cord which is attached to the opposite side of the block G and extends over the idler pulley H.

H⁴ is a weight secured to the depending end of the cord H³.

E³ is the inlet port of the cylinder E.

E⁴ is a pipe leading from the port E³ to the pipe D² to which it is connected by the valve E⁵. E⁶ is the valve arm of the valve E⁵ to which is connected a link E⁷. To the top of the link E⁶ is pivotally connected a ring E⁸. The pipe E⁴ is provided with an intermediate flexible portion E⁹.

J is a sprocket wheel also mounted on the arbor F'.

10 K is a plate held in the slotted way K' formed in the table C. The rope H² extends loosely through the plate.

K² is a boss depending from beneath the plate K.

15 K³ is a sprocket chain secured at one end to the boss K² and at the other end to the piston rod E². The sprocket chain K³ engages with the sprocket J.

L and L' are supplementary forming rollers journaled in the forked ends of the spring arms L². The spring arms L² are secured to the plate K.

20 M are grooved wheels secured to the arbor M' journaled in brackets M² secured to the main frame of the machine and suitably rotated.

25 The pole B' is carried by the wheels B into position in front of my hose making machine. The valve D³ is opened allowing compressed air to pass through the pipe D² to the port D' of the cylinder D. The piston D⁴ is forced upwardly, thereby elevating the table C and the V-block supported thereon. The V-block in its upward travel lifts the pole B' from the wheel B.

30 The table together with the cylinder E supported beneath the same rises, thereby straightening the flexible portion E⁹ of the pipe E⁴ and bringing the ring E⁸ into contact with the elbow E¹⁰. The ring E⁸, link E⁷ and valve arm E⁶ are drawn upwardly, thereby opening the valve E⁵ to the port E³ of the cylinder E. The piston E' and piston rod E² are forced forwardly drawing on the chain K³ connected to the plate K, and also rotating the wheel F and drawing on the cord H³. By this operation the block G is drawn to between the winding and forming rollers. The valve D³ is then opened to allow the air to 35 exhaust from the cylinder D and the table thereby allowed to lower to deposit the pole on the forming rollers. By the same operation the previously wound pole is raised from the forming rollers by the supplementary rollers L and L' as the table rises. The plate K is drawn to a position over the wheels M, at which position it arrives at the same time the pole B' is brought into position for deposit between the forming and winding rollers. The valve D³ is opened as before described, the wound pole lowered into the wheels M and the pole B onto the forming rollers. The spindles M¹ are driven by suitable sprocket gears to deliver the wound pole 40 to any desired point.

The pole is rotated by a suitably driven chuck which is automatically thrown into gear by the descent of the winding rollers. The winding rollers are brought into operative position by means of an air cylinder O and coacting piston and piston rod. I may use any suitable form of clutch mechanism operated by the descent of the winding rollers for connecting the chuck with its driving gear such as, an arm O' secured to the rock shaft of the winding rollers, a bell crank O² pivoted to a suitable portion of the frame, a notched bar O³ extending through bearings O⁵ at each end and through one arm of the bell crank, a spring O⁴ extending between one arm of the bell crank and a portion of the bearing, a gravity catch O⁶ normally held in the notch to the outside of the bearing, a rod O⁷ connected to the arm O' and held loosely in the arm of the bell crank and designed to strike the tail of the gravity catch when the winding rollers are lowered, a fork O⁸ at the end of the other arm of the bell crank designed to operate a cone friction clutch connecting the driving shaft and 45 clutch. Although I show this form of automatic clutch I do not desire to limit myself to this particular form, but only show it as one means of throwing my machine into connection with the driving gear.

50 From this description it will be seen that I have constructed a simple machine in which the hose and pole is quickly conveyed from the carrier wheel to the forming wheels and from the forming wheels to the delivery 55 wheels.

55 What I claim as my invention is:

1. In a hose making machine, the combination with the winding and forming rollers, of mechanism for carrying the pole supporting the hose from suitable conveyer mechanism to between the forming and winding rollers, as and for the purpose specified.

60 2. In a hose making machine, the combination with the winding and forming rollers, of mechanism for raising the pole vertically out of the grooved rollers forming part of the conveyer mechanism and then carrying the pole into the machine between the winding and forming rollers, as and for the purpose 65 specified.

65 3. In a hose making machine, the combination with the winding and forming rollers, of a table, means for raising the table vertically, a notched block longitudinally 70 movable of the table and automatic means for imparting such movement to the block by the rising of the table, as and for the purpose specified.

75 4. In a hose making machine, the combination with the winding and forming rollers, of an air cylinder, piston and piston rod, a table supported by the piston rod, a notched block held in guides on the table and means for moving the block longitudinally of the ta- 80

ble operated by the rising of the table, as and for the purpose specified.

5. In a hose making machine, the combination with the winding and the forming 5 rollers, of a vertical air cylinder, piston and piston rod, a horizontal cylinder, piston and piston rod mounted on the vertical piston, a table secured to the horizontal cylinder, a notched block movable in guides in the table, 10 a grooved wheel mounted in bearings at one end of the table, a cord connected to the wheel and to the block, an idler wheel, a cord connected to the block and depending over the idler wheel, a weight secured to the de- 15 pending cord, a sprocket wheel connected to the grooved wheel, a sprocket chain suitably secured at one end to a suitable portion of the machine and connected to the horizontal piston at the other end and designed to engage 20 with the sprocket wheel, as and for the purpose specified.

6. In a hose making machine, the combination with the winding and forming rollers, of a vertically movable table, means for 25 imparting such movement to the table, a plate movable in guide ways in the table, forming rollers mounted thereon and rotat- 30 ing receiving grooved wheels designed to receive the pole as and for the purpose specified.

7. In a hose making machine, a vertically 35 movable table, a notched block movable in guide ways thereon, means for imparting such movement to the table and to the block, as and for the purpose specified.

8. In a hose making machine, the combination with the table, the air cylinder, piston and piston rod on which the table is supported, a notched block held in guide ways in the 40 table, and means for imparting longitudinal movement to the blocks, as and for the purpose specified.

9. In a hose making machine, the combination with the vertically movable table, a notched block held in guide ways in the table, a grooved wheel journaled at one end of the table, an idler wheel at the other end of the table, a cord connecting the wheel to the block, a cord connected to the block and de- 45 pending over the idler wheel, a weight se- 50 cured to the depending cord and means for rotating the wheels by the rising of the table as and for the purpose specified.

10. In a hose making machine, the combi-

nation with the vertically movable table, a horizontal cylinder, piston and piston rod, a 55 notched block held in guide ways in the table, a grooved wheel journaled at one end of the table, an idler wheel at the other end of the table, a cord connecting the wheel to the block, a cord connected to the block and de- 60 pending over the idler wheel, a weight se- 65 cured to the depending cord; a sprocket connected to the grooved wheel, a sprocket chain connected to a suitable portion of the table and to the horizontal piston and engaging with the sprocket as and for the purpose specified.

11. In a hose making machine, the combination with the vertically movable table, of a notched block and forming rollers longitudi- 70 nally movable on the table, means for imparting such longitudinal movement thereto upon the completion of the vertical movement of the table and rotatable receiving wheels, as and for the purpose specified. 75

12. In a hose making machine, the combination with the vertically movable table, of a notched-block located in a guide at the outer end of the table and a plate held in a guide and supporting forming rollers located inter- 80 mediately of the length of the table, an air cylinder and coacting piston designed to elevate the table, and a cylinder and coacting piston designed to draw the block and plate longitudinally and rotatable receiving wheels 85 as and for the purpose specified.

13. In a hose making machine, the combination with the vertically movable table, the longitudinally movable notched blocks held in guides in the table and the plate carrying 90 forming rollers and also held in guides in the table, of an air cylinder, a grooved wheel journaled in the table, a cord secured to the wheel at one end and to the V-block at the other end, a sprocket secured to the grooved 95 wheel, a chain secured at one end to the longitudinally movable plate and at the other end to the piston of the air cylinder and engaging with the sprocket wheel and rotatable grooved receiving wheels as and for the pur- 100 pose specified.
